PORTABLE BORING MILL

Max Beauloye, Henry Beauloye, Jr., and Alfred F. Beauloye, San Diego, Calif.

Application December 27, 1949, Serial No. 135,264

8 Claims. (Cl. 77—2)

1

Our invention relates to a portable boring mill, and the objects of our invention are:

First, to provide a portable boring mill of this class which is arranged to be stabilized in alignment with the axis of an engine cylinder by means of the crankshaft of the engine in which the cylinders are being bored;

Second, to provide a portable boring mill of this class which may be used to bore large diameter engine cylinders in a limited amount of space or in close quarters within an engine room without removing the engine from its mounts;

Third, to provide a portable boring mill of this class which saves transportation and assembly costs on large engines which require cylinder reboring;

Fourth, to provide a portable boring mill of this class which employs the engine crankshaft as a stabilizer for the lower end of the boring bar, and employs fixtures at the upper end of the engine block for supporting the opposite end of the boring bar, whereby very accurate alignment of the boring axis of our portable boring mill is had relative to the axis of the original cylinders;

Fifth, to provide a portable boring mill of this class which will serve in a machine shop for the purpose of performing various boring mill functions;

Sixth, to provide a portable boring mill of this class which may be used in a lathe;

Seventh, to provide a portable boring mill of this class which is very light in weight in proportion to the large size of cylinders it is capable of boring;

Eighth, to provide a portable boring mill of this class which is particularly adapted for use in boring the cylinders of large boat engines without removing the same;

Ninth, to provide a boring mill of this class having a constant feed and fast lead screw return during the normal rotational direction of the boring bar;

Tenth, to provide a portable boring mill of this class having a bearing fixture engageable with a journal of an engine crankshaft which is provided with a V-block portion engageable with the entire length of the journal, whereby ninety degree alignment with the crankshaft journal is provided, so that the axis of the cylinder being rebored will be precisely ninety degrees to the axis of the engine crankshaft;

Eleventh, to provide a portable boring mill of this class having the nut and lead screw internally of the boring bar, whereby it is protected

2

from abrasion and various foreign matter, such as chips or the like; and

Twelfth, to provide a portable boring mill of this class which is very simple and economical of construction in proportion to its utility, very efficient, and which will not readily deteriorate or get out of order.

With these and other objects in view, as will appear hereinafter, our invention consists of certain novel features of construction, combination and arrangement of parts and portions, as will be hereinafter described in detail and particularly set forth in the appended claims, reference being had to the accompanying drawings and to the characters of reference thereon, forming a part of this application, in which:

Fig. 1 is a side elevational view of our portable boring mill, shown in an engine cylinder, which is illustrated by dash lines, and shown fixed to the crankshaft of an engine, also illustrated by dash lines; Fig. 2 is an enlarged fragmentary sectional view, taken from the line 2—2 of Fig. 1, showing parts and portions in elevation to facilitate the illustration; Fig. 3 is an enlarged fragmentary sectional view, taken from the line 3—3 of Fig. 2; Fig. 4 is an enlarged plan sectional view, taken from the line 4—4 of Fig. 1, showing parts in elevation to facilitate the illustration; Fig. 5 is a fragmentary sectional view, taken from the line 5—5 of Fig. 4; and Fig. 6 is an enlarged fragmentary sectional view, taken from the line 6—6 of Fig. 1.

Similar characters of reference refer to similar parts and portions throughout the several views of the drawings.

The main bar 1, bearings 2 and 3, bearing fixtures 4 and 5, tool carriage 6, tool holder 7, tool 8, key 9, lead screw 10, lead screw nut 11, keys 12 and 13, bushings 14 and 15, collar 16, bearing retainer 17, bearing blocks 18 and 19, gears 20 and 21, stop latches 22, 23 and 24, drive shaft 25, gear restraining shaft 26, cam 27, sheave 28, arm 29, bearing fixture supports 30, belt 31, and the crankshaft-engaging chain 32, constitute the principal parts and portions of our portable boring mill.

The boring bar 1 is a hollow tubular member, having a longitudinal slot 1a in its side wall, through which the key 9 extends. This key 9 is fixed to the tool carriage 6 by means of screws 6a, and the tool carriage 6, as shown in Figs. 1 and 4 of the drawings, is a collar-shaped hollow cylindrical member surrounding the main bar 1, and provided with a fixture 6b in which the tool holder 7 is slidably mounted and fixed by means of

key 6c and set screw 6d. It will be noted that the key 6c and set screw 6d serve to fix the tool holder 7 in the laterally disposed opening 6e in the fixture 6b, so that the tool holder 7 extends at right angles to the axis of the main bar 1, and supports the removable tool 8, which is a conventional cutting tool.

Screw-threaded in the inner end of the tool holder 7 is an adjustment screw 7a, which provides for the radial adjustment of the tool 8 together with the holder 7, for setting the same to a predetermined cutting diameter for boring a certain sized hole or cylinder. Fixed in the normally upper end of the main bar 1 is a bearing block 18, in which the pressed bushing 15 supports the collar 16, fixed to the outer side of the lead screw 10, whereby the collar 16 provides a bearing within the bushing 15 for rotation of the lead screw within the bearing block 18. This bearing block 18 is fixed to the main bar 1 by means of screws 18a, which also serve as connection screws for the main bar 1 and the drive shaft 25, which is a hollow drive shaft having an enlarged hollow portion 25a and reduced hollow portion 25b, on which the sheave 28 is fixed for driving or rotating the shaft 25 by means of the belt 31, operating in connection with a motor which is not shown in the drawing and which is no part of our present invention. The drive shaft 25 is supported in a self-aligning bearing 3, which in turn is supported in the bearing fixture 5, adapted to be secured in fixed relationship with the upper portion of an engine block, as illustrated by dash lines A in Fig. 1 of the drawings, by means of the bearing fixture supports 30.

These bearing fixture supports 30 are each provided with a hollow cylindrical portion 30a, having a split end portion 30b, provided with an internally tapered threaded nut 30c, which is adapted to cause contraction of the hollow cylindrical portion 30a around the studs 30d for holding the same in certain fixed elevated position. It will be noted that the normally lower ends of the tubular members 30a are provided with lugs 30e, through which conventional studs extend for securing the same to the upper end of the engine block A. The normally upper ends of the studs 30d are provided with shoulder portions and nuts 30f, which engage the bearing fixture 5 in which the self-aligning bearing 3 is supported, all as shown best in Figs. 1 and 2 of the drawings.

The lower end of the main bar 1 is provided with a bearing block 19, fixed therein by means of the pins 19a, and this bearing block 19 is provided with a projecting stub 19b, on which the bearing 2 is positioned. This bearing 2 is retained in the bearing fixture 4, as shown in Fig. 6 of the drawings, by means of the bearing retainer 17, which is fixed by screws 17a to the normally upper end of the bearing fixture 4. Screw threaded in the stub 19b of the bearing block 19 is a bolt 19c, having an engaging washer 19d, abutting the inner rotatable race 2a of the bearing 2, providing for the rotatable support of the normally lower end of the main bar 1.

Fixed in the internal bore 19e of the bearing block 19 is the bushing 14, which provides a bearing for the lower stub end 10a of the lead screw 10. It will be noted that the collar 16, secured to the lead screw 10 as hereinbefore described, is provided with an enlarged flange portion 16a, which provides for the limitation of

end play of the lead screw 10 in one direction, while the nut 10b, screw threaded on the normally upper end of the lead screw 10 at its reduced in diameter portion 10c, maintains the shoulder 16a of the collar 16 in its end play engagement with the end of the bushing 15. It will be noted that the threads of the nut 10b are substantially close tolerance threads, so that they fit the threads on the reduced shaft portion 10c very tightly.

It will be noted that the end of the bushing 14 surrounding the bearing stub 10a of the lead screw 10 also provides for end play restriction of the lead screw 10. The lead screw 10 is screw-threadably engaged by the traversing nut 11, as shown best in Fig. 5 of the drawings. This traversing nut 11 is provided with external screw threads at its opposite ends, engaged by the internally screw threaded key nuts 12 and 13. These key nuts 12 and 13 engage the T-head portions 9a and 9b of the key 9, respectively, for securing the nut 11 to the key 9, which is fixed, as hereinbefore described, to the carriage 6 by means of the screws 6a.

The bearing block 18, hereinbefore described, is provided with a radially disposed slot 18b, engageable with the stop latch 22, which is a reciprocally movable latch provided with a spring 22a, tending to urge the latch into the slot 18b for interlocking the rotary motion of the main bar 1 and the holder 20a of the internal spur gear 20. This internal spur gear 20 is substantially cup-shaped, and provided with a cam-engaging opening 20b, which engages the eccentric cam portion 27a of the cam 27, which is fixed to the shaft 26 by means of the pin 27b. Fixed on the upper end of the shaft 26 is the arm 29.

It will be here noted that the nut 10b hereinbefore described, is engaged by the cam member 27 at its normally upper surface, and that the lead screw 10, at its shoulder adjacent the reduced diameter portion 10c, engages the cam portion 27a of the cam member 27 axially. As shown in Fig. 3, the cup-shaped internal spur gear 20 is disclosed wherein the bottom portion 20c thereof having the opening 20b, engages the eccentric cam portion 27a of the cam member 27, through which the reduced in diameter portion 10c of the lead screw 10 extends.

The gear 21 is fixed to the lead screw 10 and is constantly in mesh with the internal spur gear 20. It will be noted that the gear 21 is substantially smaller in diameter than the gear 20, and actually has one tooth less than the gear 20, whereby one eccentric cycle of the gear holder 20a causes the lead screw 10 to rotate an amount equal to one tooth of the gear 21 in advancement over the rotation of the main bar 1. This is due to the fact that the gear 20, in constant mesh with the gear 21, is provided with one more tooth than the gear 21.

The bearing fixture 4, at the normally lower end of the main bar 1, as hereinbefore described, is provided with a V-block portion 4a, which is adapted to engage crankshaft connecting rod bearing journals as illustrated by dash lines B in Fig. 1 of the drawings, for supporting the main bar 1 in axial alignment with the cylinder bore A, as shown in Fig. 1 of the drawings. The V-block portion 4a of the bearing fixture 4 is precisely at right angles to the axis of the main bar 1, as supported in the bearing 2, held by the bearing fixture 4. Thus, the axial disposition of the bearing journal B insures proper alignment of the

main bar 1 in the cylinder A during reboring of the cylinder.

The operation of our portable boring mill is substantially as follows: When our portable boring mill is properly set up in an engine cylinder, as shown in Fig. 1 of the drawings, and engaged with the engine crankshaft, as hereinbefore described, reboring of the cylinder A may be accomplished. It is to be noted, however, that the bearing fixture 4 is secured to the journal B of the crankshaft of the engine when it is at top dead center position. This position is determined and set by a means which is no part of our present invention.

In setting up our portable boring mill on an engine block, the bearing fixture supports 30, as hereinbefore described, are secured in position for holding the bearing fixture 5, in which the bearing 3 is mounted for centrally supporting the upper end of the main bar 1 in the cylinder bore A. As the screw 32a of the chain 32 is tightened, the chain 32 forces the bearing fixture, at its V-block 4a, to intimately engage the connecting rod journal B of the engine crankshaft, which automatically aligns the axis of the main bar 1 at right angles with the journal B. Thus, when the portable boring bar is properly set up, as shown in Fig. 1 of the drawings and as hereinbefore described, the latch 22 is engaged with the slot 18b, as shown in Fig. 2 of the drawings, and a suitable motor is used to rotate the sheave 23, which in turn rotates the hollow shaft 25b, concurrently rotating the main bar 1, which, by means of the key 9, rotates the carriage 6 and lead screw nut 11 in unison. The carriage 6 carries the tool holder 7, the cutting tool 8 concentrically bores the cylinder A, straightening it up and removing the taper therefrom.

Preliminary setting of the tool 8 is accomplished radially by means of the screw 1a, as hereinbefore described, to provide for a predetermined finish diameter of the cylinder bore A. The arm 29, in connection with the shaft 26, is fixed against rotation by engaging the same with a stationary object in connection with the engine block, and the cam 27 is thus maintained in stationary position, so that the eccentric portion 27a forms an eccentric bearing around which the bearing holder 20a oscillates, carrying the internal spur gear 20 in oscillatory fashion around the spur gear 21, which is fixed to the lead screw 10. For each oscillating eccentric cycle of the gear 20, the lead screw 10, by means of the gear 21, is rotationally advanced in reverse of the main bar 1 equal to one tooth of the gear 21, inasmuch as the gear 20 is provided with a tooth additional to the number on the gear 21.

Thus, the lead screw 10 is constantly rotated slightly in advance of the rotational speed of the main bar 1, whereby the lead screw 10 slowly advances the nut 11 axially of the main bar 1, moving the carriage progressively and uniformly longitudinally of the cylinder bore A during continuous rotation of the main bar 1, which provides for a very smooth and progressively helical cutting finish inside the cylinder bore A.

It will be noted that the end 22b of the stop latch 22 reciprocates in the slot 18b during oscillatory movement of the holder 20a of the internal spur gear 20. When it is desired to retract the carriage 6 upwardly, the latch member 22 is released from the slot 18b at its end 22b and the latch 23 is reciprocated into engagement with the latch member 24, interlocking the stationary shaft 26 and the spur gear holder 20a. This

causes stationary maintenance of the lead screw 10 by the gear 21 in mesh with the gear 20, which permits the nut 11 to rotate about the lead screw 10 at a very fast rate, due to the fact that the main bar 1 revolves the nut 11 one complete revolution around the lead screw 10 for each revolution of the main bar 1. Thus, the carriage 6 is rapidly retracted upwardly longitudinally of the main bar 1 when the latch members 23 and 24 are engaged, and this, as hereinbefore described, is accomplished by continually rotating the main bar 1 in the same direction as it is normally rotated when feeding the carriage downwardly in the cylinder bore A and reboring the cylinders.

Though we have shown and described a particular construction, combination and arrangement of parts and portions, we do not wish to be limited to this particular construction, combination and arrangement, but desire to include in the scope of our invention the construction, combination and arrangement substantially as set forth in the appended claims.

Having thus described our invention, what we claim as new and desire to secure by Letters Patent is:

1. In a portable boring mill, a boring bar, bearings rotatably supporting said boring bar at each of its ends, a tool carriage longitudinally slidably mounted on said bar, said bar provided with a slot in its side wall, a key fixed to said carriage extending through said slot, a nut on the inner end of said key, a lead screw threadably engaged with said nut internally of said bar, a stationary cam, an eccentrically oscillating gear holder engaging said cam, an internal spur gear in said gear holder, and a second gear of smaller diameter in mesh with said internal spur gear and fixed to said lead screw.

2. In a portable boring mill, a boring bar, a bearing adapted to rotatably support said boring bar at each of its ends, a bearing fixture at the normally upper end of the boring bar to secure one of said bearings in fixed relationship with an engine cylinder bore, the other of said bearings having a fixture engageable with an engine crankshaft journal, said bearing fixture having means engageable with said journal for aligning the axis of said boring bar at right angles to the axis of an engine crankshaft on which said journal is disposed, a tool carriage longitudinally slidably mounted on said bar, said bar provided with a slot in its side wall, a key fixed to said carriage extending through said slot, a nut on the inner end of said key, a lead screw threadably engaged with said nut internally of said bar, means for rotating said bar in said bearings, a stationary cam, an eccentrically oscillating gear holder engaging said cam, an internal spur gear in said gear holder, and a second gear of smaller diameter in mesh with said internal spur gear and fixed to said lead screw.

3. In a portable boring mill, a boring bar, a bearing adapted to rotatably support said boring bar at each of its ends, a bearing fixture at the normally upper end of the boring bar to secure one of said bearings in fixed relationship with an engine cylinder bore, the other of said bearings having a fixture engageable with an engine crankshaft journal, said bearing fixture having means engageable with said journal for aligning the axis of said boring bar at right angles to the axis of an engine crankshaft on which said journal is disposed, a tool carriage longitudinally slidably mounted on said bar, said bar provided with a slot in its side wall, a key fixed to said car-

riage extending through said slot, a nut on the inner end of said key, a lead screw threadably engaged with said nut internally of said bar, means for rotating said bar in said bearings, a stationary cam, an eccentrically oscillating gear holder engaging said cam, an internal spur gear in said gear holder, and a second gear of smaller diameter in mesh with said internal spur gear and fixed to said lead screw, the eccentricity of said cam adapted to oscillate said gear holder equal to the radius difference between said gears.

4. In a portable boring mill, a boring bar, a bearing adapted to rotatably support said boring bar at each of its ends, a bearing fixture at the normally upper end of the boring bar to secure one of said bearings in fixed relationship with an engine cylinder bore, the other of said bearings having a fixture engageable with an engine crankshaft journal, said bearing fixture having means engageable with said journal for aligning the axis of said boring bar at right angles to the axis of an engine crankshaft on which said journal is disposed, a tool carriage longitudinally slidably mounted on said bar, said bar provided with a slot in its side wall, a key fixed to said carriage extending through said slot, a nut on the inner end of said key, a lead screw threadably engaged with said nut internally of said bar, means for rotating said bar in said bearings, a stationary cam, an eccentrically oscillating gear holder engaging said cam, an internal spur gear in said gear holder, and a second gear of smaller diameter in mesh with said internal spur gear and fixed to said lead screw, the eccentricity of said cam adapted to oscillate said gear holder equal to the radius difference between said gears, means for maintaining said cam stationary during rotation of said gear.

5. In a portable boring mill, a boring bar, a bearing adapted to rotatably support said boring bar at each of its ends, a bearing fixture at the normally upper end of the boring bar to secure one of said bearings in fixed relationship with an engine cylinder bore, the other of said bearings having a fixture engageable with an engine crankshaft journal, said bearing fixture having means engageable with said journal for aligning the axis of said boring bar at right angles to the axis of an engine crankshaft on which said journal is disposed, a tool carriage longitudinally slidably mounted on said bar, said bar provided with a slot in its side wall, a key fixed to said carriage extending through said slot, a nut on the inner end of said key, a lead screw threadably engaged with said nut internally of said bar, means for rotating said bar in said bearings, a stationary cam, an eccentrically oscillating gear holder engaging said cam, an internal spur gear in said gear holder, and a second gear of smaller diameter in mesh with said internal spur gear and fixed to said lead screw, the eccentricity of said cam adapted to oscillate said gear holder equal to the radius difference between said gears, means for maintaining said cam stationary during rotation of said bar, radial slot means in connection with said bar, and a projecting latch on said gear holder for interengaging the same during rotation of said bar and concurrent rotation and eccentric oscillation of said gear holder.

6. In a portable boring mill, a hollow rotating boring bar, means for rotating the same, a lead screw rotatably mounted in said boring bar, a tool carriage slidable on said boring bar, having means

connected therewith threadably engaged with said lead screw, a spur gear on said lead screw, an internal spur gear in mesh with said first-mentioned gear and having greater pitch diameter, a holder for said second-mentioned gear, stationary eccentric cam means adapted to oscillate said gear holder when rotated about the axis of said lead screw, whereby the different diameters of said gears cause said lead screw to be rotationally advanced relative to the rotation of said bar.

7. In a portable boring mill, a hollow rotating boring bar, means for rotating the same, a lead screw rotatably mounted in said boring bar, a tool carriage slidable on said boring bar, having means connected therewith threadably engaged with said lead screw, a spur gear on said lead screw, an internal spur gear in mesh with said first-mentioned gear and having greater pitch diameter, a holder for said second-mentioned gear, stationary eccentric cam means adapted to oscillate said gear holder when rotated about the axis of said lead screw, whereby the different diameters of said gears cause said lead screw to be rotationally advanced relative to the rotation of said bar, latch means engaging said gear holder with said bar and adapted to reciprocate radially with said gear holder, means for holding said cam stationary against rotation during rotational movement of said bar, and secondary latch means engageable with said means for holding said cam stationary, and connected to said gear holder, whereby said lead screw may be reversed at a rapid rate when said first-mentioned latch means is released from said bar.

8. In a portable boring mill, a hollow rotating boring bar, means for rotating the same, a lead screw rotatably mounted in said boring bar, a tool carriage slidable on said boring bar, having means connected therewith threadably engaged with said lead screw, a spur gear on said lead screw, an internal spur gear in mesh with said first-mentioned gear and having greater pitch diameter, a holder for said second-mentioned gear, stationary eccentric cam means adapted to oscillate said gear holder when rotated about the axis of said lead screw, whereby the different diameters of said gears cause said lead screw to be rotationally advanced relative to the rotation of said bar, latch means engaging said gear holder with said bar and adapted to reciprocate radially with said gear holder, means for holding said cam stationary against rotation during rotational movement of said bar, and secondary latch means engageable with said means for holding said cam stationary, and connected to said gear holder, whereby said lead screw may be reversed at a rapid rate when said first-mentioned latch means is released from said bar, said cam means eccentric equal to the difference in the radius of the pitch diameter of said gears.

MAX BEAULOYE.
